UNITED STATES PATENT OFFICE.

JOHN ROBERT TOMLIN, OF BROOKLYN, NEW YORK, ASSIGNOR TO INTERTYPE CORPORATION, OF BROOKLYN, NEW YORK, A CORPORATION OF NEW YORK.

TYPOGRAPHICAL MACHINE.

Application filed June 10, 1926. Serial No. 114,990.

The present invention relates to improvements in typographical machines of the class shown and described in U. S. Patent No. 436,532, granted September 16, 1890, employing character-bearing matrices and expansible spacers which, by appropriate mechanism, are drawn from their magazines or places of storage and assembled into a line, the line is justified and a cast is taken therefrom to produce a type bar or slug, after which the matrices and spacers used in the line are returned to the magazines or their places of storage. The invention relates more particularly to machines of this general class which are adapted for the assembling of matrices belonging to different fonts as the nature of the composition may require, for which purpose it is preferable to employ a plurality of superposed magazines to contain the different fonts of matrices, and to provide means for shifting the magazines to bring one or another thereof into position to deliver the desired matrices for assembly into the line and to receive such matrices which are returned thereto after a cast has been made from the matrix line.

One of the objects of the present invention is to provide improved means whereby the shifting mechanism and the operative support for the magazines constitute parts of the main frame of the machine, thereby insuring permanency and stability in the shifting movements and the positioning of the magazines and the maintenance of the correct working relationship of each of the magazines with the cooperating mechanisms of the machine, the weight of the parts which require shifting being also reduced so that the shifting of the magazines may be accomplished with greater ease and facility.

Another object of the invention is to provide a novel and improved multiple magazine unit and mechanism for shifting it whereby the weight of the magazine unit is so balanced as to enable it to be easily shifted to bring the different magazines into position for operation or rocked to carry the magazines into position for removal and, moreover, the shifting movements of the magazines may be caused to take place in such a manner as to equalize or distribute the load and thereby enable the magazine-shifting operations to be performed with less effort.

Another object of the invention is to provide means for so coordinating the lifting and travelling movement of the forward ends of the magazines during shifting thereof as to insure clearance between the magazines and the upper ends of the reeds or escapement actuating devices during each magazine shifting operation.

A further object of the invention is to provide means which locks or holds the magazines in their respective operative positions when they have been brought into such positions, thereby preventing accidental displacement of a magazine from its operative position after it has been brought into such position although permitting the magazine-shifting mechanism to be operated to remove a magazine from operative position and to bring another magazine into such position when such is desired.

To these and other ends, the invention consists in certain improvements and combinations and arrangements of parts, all as will be hereinafter more fully described, the features of novelty being pointed out particularly in the claims at the end of the specification.

In the accompanying drawings:

Figure 1 is a side elevation of the upper portion of a typographical machine of the general class hereinbefore referred to, to which the present invention is applied;

Figure 2 is a detail view, partly in section, showing the manner of mounting one side of the magazine unit on the main frame of the machine;

Figure 3 is a detail view in side elevation and on an enlarged scale, of the magazine unit and its support, this view illustrating diagrammatically the movement of the magazine unit while it is being shifted to remove one magazine from operative position and to bring another magazine into such position;

Figure 4 is a fragmentary detail view, partly in section, illustrating a portion of the shifting mechanism and showing one of the magazines at another phase in its shifting movement;

Figure 5 is a front elevation, partly in section, illustrating the supporting and shifting mechanism for the magazine unit;

Figure 6 is a diagrammatic view illustrating the operative movements of the magazine shifting mechanism and indicating the man-

2
ner in which a magazine will be locked or retained in operative position and thus prevent its displacement;

5 Figure 7 is a side elevation of the upper portion of a typographical machine showing a modified form of magazine support;

Figure 8 represents a section taken on the line 8—8 of Figure 7;

10 Figure 9 is a view similar to Figure 7 but showing another modified form of magazine support; and

15 Figure 10 is a fragmentary detail view showing in top plan one side of the magazine unit and the adjacent side frame and illustrating the lugs and cooperating recess for seating the magazine unit in different operative positions.

Similar parts are designated by the same reference characters in the several figures.

20 The present invention is applicable generally to typographical machines of the class shown and described in the patent hereinbefore referred to, although it is particularly applicable to machines of this class which 25 are adapted to contain a plurality of superposed magazines containing different fonts of matrices which are capable of being assembled in a line as the nature of the matter in course of composition may demand. The 30 preferred embodiments of the invention are shown in the accompanying drawings and will be hereinafter described in detail, but it is to be understood that the invention is not restricted to the precise construction 35 shown as the scope of the invention is indicated by the claims.

In the present instance, the machine, which 40 may be in general of the class shown and described in said Letters Patent, is adapted to contain three superposed magazines designated 10, although the unit may contain a greater or less number of magazines. Each magazine may be of the construction usual in machines of this general class and may 45 contain any desired font of matrices, the lower ends of the magazines being equipped with escapements 10^a which serve to retain the the matrices therein although effecting delivery of matrices when actuated by the 50 usual keyboard mechanism of the machine to which the escapements are operatively related when the magazine is in operative position. Each magazine is mounted on a magazine frame 11, these frames supporting 55 the respective magazines and preventing them from sliding forward when the magazines are in their normal forwardly and downwardly inclined position, as shown by the full lines in Figure 1, but permitting 60 any one or more of the magazines to be removed therefrom by sliding such magazine or magazines rearwardly while the magazine unit is rocked into a rearwardly and downwardly inclined position, as indicated by the 65 dotted lines in Figure 1. Side plates 11^a

are secured to the opposite side edges of the magazine frames 11, a multiple magazine unit being thus formed which comprises the magazines 10 and their frames 11.

The magazine unit just described is operatively supported in the machine by a pair of side brackets 12 and 13, these side brackets being secured to and constituting parts of the main frame of the machine. In machines of this general class, the main frame is 75 usually composed of a number of separate parts or components which are secured to one another to form a rigid supporting structure. For example, the distributor bracket 15 commonly used on machines of this class 80 to support the distributor mechanism, the intermediate bracket 16 which supports the keyboard mechanism of the machine, and the bracket 17 which forms a tie between the brackets 15 and 16 are bolted together and 85 form parts or components of the main frame, and in the construction illustrated in Figures 1 and 3, the front portion of the bracket 12 is secured to the intermediate bracket 16 by a bolt 20 while the rear portion of the 90 bracket 12 is provided with a laterally extending stud or trunnion 21 which is secured permanently thereto or is formed integrally therewith, this stud engaging in an aperture 22 which is formed in an arm 23 which is a 95 part of the distributor bracket. The bracket 13 is secured at its forward end to the column 18 which is a permanent and rigid part of the machine frame, by the bolt 24, and this bracket 13 is provided at its rear portion 100 with a laterally extending stud 25 which is secured permanently thereto or is formed integrally therewith, this stud engaging in an aperture 26 formed in the distributor bracket 15. Thus the brackets 12 and 13 105 which serve to support the magazine unit become permanent or fixed components of the main frame of the machine when they are secured in place.

A shaft 30 is journaled to or extends transversely through the intermediate magazine frame 11 and this shaft has rollers 31 journaled thereon at the opposite sides of said frame, as is shown in Figure 5. The ends of the shaft 30 are fitted into the upper ends of a pair of links 32, they being fixed to the links by the pins shown or other suitable means, the lower ends of the links being operatively connected with the magazine shifting mechanism as will be hereinafter set forth. The rollers 31 are guided and supported by inclined rails 33 which are formed on the upper portions of the side brackets 12 and 13, the rollers being adapted to ride upon these rails during the shifting movements of the magazine unit, whereby the shaft 30 which pivotally supports the upper portion of the magazine unit is guided to move rectilinearly in a forward or rearward direction with respect to the main frame 130

The lower portions of the brackets 12 and 13 are formed with slots 34 which are parallel with the upper rails 33, and gear racks 35 are secured to the brackets, these racks 5 extending longitudinally of the respective slots and being mounted so that their pitch lines are in the same plane with the surfaces 36 at the bottoms of these slots and which serve as rails.

10 The shifting mechanism for the magazine unit is supported to travel on the rail surfaces 36 and such shifting mechanism cooperates with the racks 35 and with the links 32. The shifting mechanism as shown comprises a pair of pinions 40 which are located at the inner sides of the frames 12 and 13 and are fixed to shafts 41 which extend outwardly through the slots 34 in these frames, the pinions meshing with the racks 35 which are fixed to the respective side frames. Anti-friction rollers 42 are preferably mounted on the shafts 41 so that they fit the slots 34 in the side frames and ride upon the rails 36 formed at the lower edges 20 of these slots. The shafts 41 are connected by a shaft 43 which is located eccentrically of the shafts 41, the latter shafts having their centers in alignment. As shown, the ends of the shaft 43 are rigidly fixed to the inner ends of the shafts 41 by cranks 44 and 45. The shaft 43 extends across the space between the inner ends of the shafts 41 and has anti-friction rollers 46 journaled thereon, these rollers being arranged to ride against the surface 46^a which is formed at the forward under side of the lower magazine frame 11, this surface being preferably inclined substantially at the angle shown. The magazine shifting mechanism is operated by a crank or handle 47 which is fixed to the outer end of one of the shafts 41, it being preferably fixed to the right-hand shaft for convenience of operation. The shafts 41 in the preferred construction are provided at the outer sides of the frames 12 and 13, with eccentrics 48 which are fixed to these shafts by the pins 49 or other suitable means, the centers of these eccentrics being preferably located in a line between the centers of the shafts 41 and 43 so that these eccentrics and the shaft 43 are offset at substantially the same angle with respect to the shafts 41. The lower ends of the links 32 are formed as bearings or straps 50 which fit the respective eccentrics 48. It will be observed that the magazine-shifting mechanism just described embodies a double eccentric mechanism which comprises the shaft 43 which is eccentric to the shafts 41 and the link-operating eccentrics 48 which are also eccentric with respect to the shafts 41.

In order to insure proper registration of the lower end of each magazine with the

matrix assembler entrance 55 and the upper end of the magazine with the channel entrance 56 which leads from the matrix distributor, when any one of the magazines is brought into operative position, the side plates 11^a toward the lower forward end of the magazine unit are provided with suitably positioned lugs 57 which project outwardly therefrom and the side frames 12 and 13 which are spaced apart sufficiently to permit these lugs to pass between them are provided with inwardly opposite portions formed with suitably positioned recesses 58 arranged in the path of the lugs, these lugs and recesses being so located that a pair of lugs on the magazine unit will engage 75 the recesses 58 in the side frames as each magazine in the unit approaches the working or operative position, these lugs and recesses thus serving to insure proper position of the lower and upper ends of the magazine thus brought into operative position with respect to the assembler entrance and channel entrance.

In assembling magazine supporting and shifting means constructed as hereinbefore described, the brackets 12 and 13 are first placed between the arms of the distributor bracket 15 so that the studs 21 and 25 on these brackets will enter the apertures 22 and 26 in the distributor bracket, after which the side frames 12 and 13 are moved laterally outwardly to fully insert the studs 21 and 25 in said apertures. The forward end of the bracket 12 comes against the adjacent side of the bracket 16 to which it is secured by insertion of the bolt 20 and the forward end of the bracket 13 fits against the column 18 to which it is secured by insertion of the bolt 24. If desired, the studs 21 and 25 may be locked in the respective apertures in the distributor bracket by the insertion and tightening of the set screws 59 carried by the distributor bracket. When the side brackets 12 and 13 are mounted, they are rigidly secured to the main frame 10 and become parts or components thereof. After these brackets have been mounted, the magazines, magazine frames, the magazine supporting shaft 30 and its rollers and links, and the magazine shifting mechanism may be separately positioned and assembled to form the operative device. Removal of the side brackets or either of them is precluded while the magazine unit is in position between them, and the magazine unit is maintained between the side brackets by the supporting shaft and the magazine shifting mechanism which is coupled thereto.

The operation is as follows: Assuming the magazine unit occupies the full line position shown in Figure 1 and that it is desired to shift the unit to bring the intermediate or the lower magazine into operative position,

this shifting operation is effected by turning the handle 47 in an anticlockwise direction, as viewed in Figure 1, through one or two revolutions, according to which magazine is to be brought into position for use. Turning of the handle 47 effects rotation of the shafts 41, and as the pinions 40 are fixed to these shafts, the pinions will rotate and, in so doing, they will travel forwardly on the racks 35 with which they engage. The shaft 43 which is fixed to the shafts 41 in eccentric relation thereto will, as a result of the rotating and traversing movement of the pinions, swing through an approximately cycloidal path. While a magazine is in operative position, its escapements are located immediately above and in operative relation with the upper ends of the reeds or escapement actuating members 60 which are carried by the bracket 16 of the main frame, but when the crank 47 is rotated in the manner stated, the rollers 46 on the eccentric shaft 43 and which bear against the surfaces 46^a on the lower magazine frame act to lift the lower or forward end of the magazine unit, the rollers 46 riding on the surfaces 46^a while the pinions move forwardly on their racks. The lifting movement thus imparted to the magazine unit causes the lower end of the magazine which was in operative position to be lifted so that its escapements are carried upwardly and away from the actuating reeds. The movement of the magazine unit in a forward and rearward direction is controlled by the links 32, the lower ends of which cooperate with the eccentrics 48 fixed to the shafts 41 and the upper ends of which are fixed to the transverse shaft 30 which supports the magazine unit.

The shiftable bearing or engagement of the shaft 43 on the surface 46^a of the magazine unit enables ample lifting and lowering movements of the matrix-delivery end of the magazine unit to be derived from the cycloidal motion of this shaft, but as the center of this shaft is outside the pitch circles of the pinions 41, it will travel in a curtate cycloid, and if this shaft had a fixed bearing on the magazine unit, the latter would receive a reverse movement before commencing its forward or rearward shift, and such reverse movement would cause interference between the matrix escapements and their actuating devices and would also preclude accurate and positive setting of the magazine unit in its different operative positions by the lugs 57 and cooperating recesses 58, or other positioning means. The free riding of the shaft 43 on the magazine unit is therefore provided to avoid such objectionable reverse motion which the magazine unit would otherwise receive and to enable the forward and rearward shifting movements of the magazine unit, incident to its removal

from one operative position and its placing in another position, to be effected by other means which acts for example through the links 32 connected to the rollers 31 which shiftable support the upper end of the 70 magazine unit.

It has been found that if the shaft 30 supporting the magazine unit is arranged to move forwardly or rearwardly in unison or synchronism with the shafts 41 during the 75 shifting operation, the resulting longitudinal movement of the magazines will be rapid with respect to the lifting action of the shaft 43 and it might tend to cause the lower ends of the magazines to collide with 80 the upper ends of the reeds. However, by connecting the shaft 30 to the shafts 41 through eccentrics on the shafts 41, as in the preferred construction hereinbefore described, a variable longitudinal movement 85 of the shaft 30 with respect to that of the shafts 41 is obtained during the shifting of the magazines, and by the use of eccentrics the centers of which are on or within the pitch circles of the pinions 40, so that 90 the eccentric centers will describe common or prolate cycloids during the forward and rearward travel of the pinions, the forward and rearward shifting movements of the magazine unit can be most advantageously 95 coordinated to the lifting and lowering movements of its matrix-delivery end.

Figure 6 shows diagrammatically the differential longitudinal movement of the shaft 30 relatively to the shafts 41 during the 100 shifting operation obtained from eccentrics whose common center 71 is located within the common pitch circle of the pinions 40, and which are connected to the shaft 30 by links 32. In this figure, the lines 61 and 62 105 represent, respectively, units of longitudinal movement of the shafts 30 and 41, these lines being provided with graduations reading from "0" to "12." The forward and rearward traversing movements of the shafts 110 41 are regular and in direct proportion to the rotation of the operating handle and, hence, the graduations on the line 62 are spaced uniformly, whereas the forward or rearward movement of the shaft 30 is variable with respect to the forward or rearward movement of the shafts 41 and, hence, the 115 graduations on the line 61 vary or are unequal. Assuming that the point "0" on the line 61 coincides with the center of the shaft 30 and that the "0" on the line 62 coincides with the center 70 of the shafts 41 before the shifting operation commences, then the first part of the rotation of the operating handle will rotate the pinions in the direction of the arrow C, and while the center 70 of the shafts 41 is moving forwardly from "0" to "1" on the line 62, the center of the shaft 30 will move forwardly through the 120 much shorter distance represented between 125 130

"0" and "1" on the line 61. During this rotation of the shaft 41, the shaft 43 is acting to lift the forward ends of the magazines, and the relatively small forward movements of the magazines at this phase of the operation enables the escapements to be disengaged from the reeds by movement of the escapements in a direction which is approximately vertical. As the rotation of the shafts 41 continues under the motion imparted thereto by the operating handle, the center 70 of the shafts 41 travels along the line 62 from the point "1" to the point "2" and during this advance of the shafts 41 the eccentric shaft 43 acts to further lift the forward ends of the magazines while at the same time the center of the shaft 30 moves forwardly along the lines 61 from the point "1" thereon to the point "2". The unit of movement between the graduations "1" and "2" on the line 61 is much less than that along the line 62 between the graduations "1" and "2", although the unit of movement between the graduations "1" and "2" is somewhat greater than that between the graduations "0" and "1" on the line 61, and, hence, the forward movement of the magazines at this phase in the operation is relatively small in comparison with the lifting movement of the shaft 43. As the shifting operation advances further, the extent of forward movement of the shaft 30 progressively increases in relation to the forward movement of the shafts 41 so that when the shaft 30 is near the middle of its forward travel during each shifting operation, the extent of its forward travel will be in excess of the forward movement of the shafts 41. As the shifting operation nears completion, the increments of forward movement of the shaft 30 diminish relatively to the corresponding increments of forward movement of the shafts 41, as is indicated by the varying spacing of the graduations along the line 61. By retarding the forward movement of the shaft 30 during the initial and final stages of the shifting operation, the eccentric shaft 43 is enabled to operate effectively to lift the escapements of the magazine previously in use out of working relation with the reeds and to lower the escapements of another magazine brought into use so that they will be in working relation with the reeds, without danger of collision between the escapements or the lower ends of the magazines with the reeds. Furthermore, by imparting an accelerated forward movement to the shaft 30 at the intermediate stage of the shifting operation, the magazine previously in use, after it has been elevated, will be shifted rapidly out of working position and the next magazine will be shifted by a rapid movement to bring its escapements into position above the reeds.

The differential traversing movement im-

parted to the shaft 30 from the shafts 41, through the eccentrics on the latter shafts and the links, not only facilitates the movement of one magazine out of operative position and the moving of another magazine into operative position with respect to the escapement actuating reeds, but it also enables the shifting operation to be performed with greater ease by equalizing or distributing the load throughout the entire shifting operation. It will be noted that while the weight of the lower ends of the magazines is being lifted by the upward movement of the shaft 43, there is a relatively small longitudinal movement of the shaft 30, but after the lower ends of the magazines have been elevated and no further energy is required for the elevating operation, the shaft 30 will travel at an accelerated speed to carry the magazine unit forwardly or rearwardly, and this increased rate of movement of the magazine unit in a forward or rearward direction does not impose any additional load upon the operating crank as no further lifting of the forward ends of the magazines is required at this stage.

Figure 3 shows in full lines the magazine unit at the stage in the shifting operation where the lower ends of the magazines have been elevated to approximately their highest point, and the dotted lines in this figure indicate the position finally assumed by the intermediate magazine as it moves into operative position, the accelerated longitudinal movement of the magazines beginning as the shifting mechanism moves from the full line position toward the dotted line position. Accurate positioning of the different magazines relatively to the assembler entrance 55 and the channel entrance 56 is insured by the lugs 57 which are positioned on the magazine unit to conform with the operative positions of the different magazines and are arranged to rest in the recesses 58 in the side brackets 12 and 13 when the respective magazine is in operative position. The dot-and-dash line "X" indicates substantially the path through which these lugs travel in moving to and from engagement with the recesses 58 when the forward and rearward shifting movements of the magazine unit are governed by the eccentrics 48, as hereinbefore described.

The double eccentric arrangement provided in the shifting mechanism not only controls the forward or rearward movement of the magazine unit during the shifting thereof to facilitate the removal of one magazine from operative position and the bringing of another magazine into such position, but it also provides a locking or holding means which will prevent accidental displacement of a magazine from operative position. This will be understood from Figure 6 which diagrammatically represents the position of the

parts of the shifting mechanism when a magazine is in operative position. In this figure 70 represents the center of the pinion shafts 41, and 71 represents the center of the eccentrics 48 on these shafts. It will be observed that if a force should act on the magazine unit to move its supporting shaft 30 forwardly or in the direction of the arrow A, a resultant force will act through the link 32 which would tend to move its lower end forwardly or in the direction of the arrow B. However, at this time, the center 71 of the eccentric engaged by the lower end of the link occupies a position between the center 70 of the pinion and the rack. The pinion will then be locked against forward movement along its rack because forward movement of the pinion along its rack would involve rotation of this pinion in the direction of the arrow C and the consequent motion of the center 71 of the eccentric in the same direction would oppose and overcome the force acting on the link 32 in a direction to move it in the direction of the line B. Similarly, if a force acted on the magazine unit in a direction to move the shaft 30 rearwardly or in the direction of the arrow D in Figure 6, a resultant upward pull would be exerted on the link 32. This force would be transferred from the link through the eccentric to the pinion and would act to move the pinion rearwardly or in the direction of the arrow E. Such rearward movement of the pinion, however, would require rotation of the pinion in the direction of the arrow F and, in consequence, the shifting mechanism would lock the magazine unit against such movement. It will, therefore, be understood that while a magazine is in operative position, it cannot be displaced accidentally from such position by a force acting to move the magazine unit either forwardly or rearwardly, but the magazine unit may be promptly shifted to carry one magazine out of operative position and to bring another magazine into such position, by mere rotation of the operating handle in the appropriate direction and through the appropriate number of revolutions. If the upper magazine is in operative position and it is desired to bring the intermediate magazine into such position, one complete rotation of the operating handle 47 in an anti-clockwise direction as viewed in Figure 1 will effect this shift; and if it is desired to remove the upper magazine from operative position and to bring the lowermost magazine into such position, two revolutions of the operating handle 47 in an anti-clockwise direction as viewed in Figure 1 will effect this result. If the intermediate or lower magazine occupies the operative position and it is desired to bring the upper magazine into such position, the shift is made by turning the operating handle 47 in a clockwise direction

through one of two revolutions, as the case may be.

When it is desired to remove a magazine from the magazine unit and replace it by another magazine, it is only necessary for the operator to grasp and pull downwardly on the handle 14 which is attached to the rear end of the lower magazine frame. The magazine unit will then be rocked from its normal forwardly and downwardly inclined position into a reverse or rearwardly and downwardly inclined position, the rocking motion taking place about the shaft 30 as a center, and during this rocking movement the surface 46^a on the lower magazine frame merely lifts out of working relation with the rollers 46 on the shaft 43. Figure 1 shows the magazine unit shifted into its rearwardly and downwardly inclined position by the dotted lines, the magazine unit being then in a position which enables any one or more of the magazines to be removed therefrom and others substituted, after which the magazine unit may be returned to its normal position as shown by the full lines in this figure, the surface 46^a on the lower magazine frame being thus restored to its normal working relation with the rollers 46 on the shaft 43. In order to hold the magazine unit in its magazine removing position, as shown by the dotted lines in Figure 1, a gravity latch 19 may be pivoted on the lower magazine frame and shaped and arranged to latch over a flange on the distributor bracket when the magazine unit has reached the proper tilted position, the latch holding the magazine unit in such position until the magazines have been changed as desired, whereupon releasing of the latch 19 from the distributor bracket will enable the magazine unit to tilt back to its normal position. The weight is so distributed in the magazine unit that the portion thereof forward of the shaft 30 is heavier than its portion in rear of said shaft so that the magazine unit by its own weight will tend to remain in its normal forwardly and downwardly inclined position and the surface 46^a on the lower magazine frame will remain in contact with the anti-friction rollers 46 on the lifting shaft 43.

The modification illustrated in Figures 7 and 8 is applicable to the usual components of the main frame of the machine, as previously described, but the rails 33^a on which the rollers which support the magazine unit ride are formed on brackets which are cast as integral parts of the distributor bracket 5, and the rail slot 34^a in which the shafts 41 of the shifting mechanism operate is formed in a bracket 17^a which is cast as an integral part of the usual tie bracket 17. The supporting and shifting mechanism may be applied to this embodiment substantially as has been described in connection with Figures 1 to 6, inclusive.

In the modification shown in Figure 9, a bracket 12^a is used which is secured at its rear end to the distributor bracket by bolts 21^a or other suitable means, and it is secured 5 at its forward end to the intermediate bracket 16 by a bolt 20. This bracket 12^a is formed on its upper edge with a rail 33^b on which may ride the roller on the corresponding end of the shaft 30, and this 10 bracket is also formed with the rail slot 34^b in which the shaft 41 of the shifting mechanism operates. The supporting and shifting mechanism may be applied to this embodiment in substantially the same manner 15 as has been described and the mode of operation is identical therewith.

I claim as my invention:—

1. A typographical machine comprising a main frame having escapement actuating 20 devices thereon, a magazine unit embodying a plurality of superposed matrix magazines having matrix controlling escapements at their delivery ends, mechanism operative to lift and lower the matrix delivery ends of 25 the magazines to engage and disengage their escapements relatively to the escapement actuating devices, and means controlled by said lifting and lowering mechanism for governing the movement of the magazine 30 unit which removes one magazine from operative position and brings another magazine into such position.

2. A typographical machine comprising a main frame having escapement actuating 35 devices thereon, a magazine unit embodying a plurality of superposed matrix magazines having matrix controlling escapements at their delivery ends, and mechanism for lifting and lowering the matrix delivery ends 40 of the magazines to engage and disengage their escapements with respect to the escapement actuating devices, and means for concurrently moving the magazines in a direction to remove one magazine from operative 45 position and bring another magazine into such position which movement is relatively retarded during the lifting and lowering operations and is accelerated while the magazines are elevated.

50 3. A typographical machine comprising a main frame having escapement actuating devices thereon, a magazine unit embodying a plurality of superposed matrix magazines, means movable in a substantially cycloidal path to raise and lower the matrix delivery ends of the magazines relatively to the escapement actuating devices, and means for shifting the magazines in a direction to remove a magazine from operative position by 55 a movement which is relatively retarded during the lifting of the magazines and is accelerated while the magazines are elevated.

65 4. A typographical machine comprising a main frame having escapement actuating de-

vices thereon, a magazine unit comprising a plurality of superposed matrix magazines, magazine shifting mechanism comprising a member movable in a cycloidal path to lift and lower the matrix delivery ends of the 70 magazines with respect to the escapement actuating devices, and means for shifting the magazines at a differential speed with respect to the cycloidal movement of said member and in a direction to remove one magazine from operative position and to bring another magazine into such position relatively to the escapement actuating devices. 75

5. A typographical machine comprising a main frame having escapement actuating devices thereon, a magazine unit embodying a plurality of superposed matrix magazines, and magazine shifting mechanism including a pinion and a cooperating rack along which it travels, a member movable by said pinion 80 through a cycloidal path and operative to lift and lower the matrix delivery ends of the magazines with respect to the escapement actuating devices, and means for moving the magazine unit at a differential rate with respect to the travel of the pinion along the 85 rack to remove one magazine from operative position with respect to the escapement actuating devices and to bring another magazine into such position. 90

6. A typographical machine comprising a main frame having escapement actuating reeds extending upwardly thereon, a plurality of inclined superposed matrix magazines, and magazine shifting mechanism 100 comprising a rack and a cooperating pinion to travel in a forward and rearward direction, a member arranged eccentrically to and rotatable with said pinion, said member being movable in a cycloidal path and operative to lift and lower the matrix delivery ends of the magazines with respect to said reeds, and means including an eccentric rotatable with said pinion to impart forward or rearward movement to the magazines at 105 a rate which is differential with respect to the travel of the pinion on its rack. 110

7. A typographical machine comprising a main frame having upwardly extending escapement actuating reeds thereon, a plurality of matrix magazines, a shaft carrying a member arranged eccentrically thereto, means for causing said shaft to travel in a forwardly or rearwardly direction when rotated, thereby causing said eccentric member 115 to travel in a cycloidal path to lift or lower the magazines with respect to said reeds, and means including an eccentric connected to said shaft for causing the magazines to move forwardly or rearwardly concurrently with 120 such movements of said shaft but at a differential rate with respect thereto. 125

8. A typographical machine comprising a main frame having tracks extending forwardly and rearwardly thereon, a plurality 130

of matrix magazines, supporting means for the magazines arranged to travel on one of said tracks, magazine shifting mechanism arranged to travel on the other track and embodying a magazine lifting and lowering member which is movable in a cycloidal path during the forward or rearward movement of the shifting mechanism, and means for causing the magazine supporting means to travel on its track at a differential rate with respect to the travel of the shifting mechanism on its track.

9. A typographical machine comprising a main frame having tracks thereon, a magazine unit embodying a plurality of matrix magazines, means cooperative with the magazine unit to support it for forward and rearward movement on one of the tracks, shifting mechanism arranged to travel on the other track and embodying a member movable in a cycloidal path during such movement of said mechanism to lift or lower the matrix delivery ends of the magazines, and means including an eccentric connecting the shifting mechanism and the magazine supporting means for causing a differential movement of the latter on its track with respect to the movement of the shifting mechanism on its track.

10. In a typographical machine having a main frame and a magazine unit embodying a plurality of superposed matrix magazines, mechanism for supporting the magazines in the main frame and for shifting them to bring one or another thereof into operative position comprising a supporting shaft guided to move forwardly and rearwardly on the main frame, an operating shaft also guided to move forwardly and rearwardly on the main shaft and having means for moving it forwardly or rearwardly when rotated, a member arranged eccentrically to said operating shaft and movable, during rotation of the latter, through a cycloidal path to lift and lower the magazines, an eccentric also connected to the operating shaft, and means connecting said eccentric to said supporting shaft whereby the magazines are shifted forwardly or rearwardly during the rotating and forward or rearward movement of the operating shaft.

11. In a typographical machine having a main frame and a magazine unit embodying a plurality of superposed matrix magazines shiftable therein, supporting and shifting mechanism for the magazine unit comprising a member movable in a cycloidal path to raise and lower the magazines and means for controlling the forward and rearward movements of the magazine unit and for locking said unit against displacement while a magazine therein is in operative position.

12. In a typographical machine having a main frame, and a magazine unit embodying a plurality of matrix magazines shift-

able thereon to bring one or another of the magazines into operative position, supporting and shifting mechanism for the magazine unit comprising an operating shaft and eccentric devices connected thereto, one of said eccentric devices being operative to lift and lower the magazines and the other eccentric device being connected to the magazine unit and operative to control its shifting movements and to lock the magazine unit 75 against displacement while a magazine therein is in operative position.

13. In a typographical machine, the combination with the main frame having brackets forming parts thereof, and a magazine unit embodying a plurality of superposed matrix magazines mounted between said brackets, of a supporting member connected to the magazine unit and about which said unit is adapted to rock into a forwardly 80 and downwardly inclined position for operation and into a rearwardly and downwardly inclined position for removal of magazines, said supporting member being guided to shift in a forwardly and rearward direction 85 on said brackets, and an operating member mounted to shift forwardly and rearwardly in said brackets and rotatable to lift and lower the matrix delivery ends of the magazines, said operating member being unattached to but arranged to act on the magazine unit, and means connecting said supporting and operating members whereby the forward and rearward shifting movements 90 of supporting member and the magazines 95 connected thereto are controlled by the rotation and shifting movements of the operating member.

14. A typographical machine comprising a main frame, a magazine unit embodying a plurality of superposed magazines shiftable relatively to the main frame to bring one or another of the magazines into operative position and also rockable to carry the magazines into magazine removing position, 105 and mechanism in the main frame of the machine for supporting and shifting the magazine unit embodying a supporting shaft on which the magazine unit is adapted to rock and which is shiftable in the main frame, an operating shaft having means which is unattached to but is operative on the magazine unit to lift and lower the magazines, and means operatively connecting the operating shaft to the supporting shaft whereby the shifting movements of the latter and the magazine unit are controlled by the operating shaft.

15. A typographical machine comprising a main frame, a magazine unit embodying a plurality of superposed matrix magazines, rollers pivotally supporting said unit on an axis which is shiftable rectilinearly in a direction forwardly and rearwardly of the main frame, an eccentric shaft shiftable for- 125 130

wardly and rearwardly with respect to the main frame and operative to lift and lower the matrix-delivery ends of the magazines, and links connecting said shaft to said rollers and operative to govern the shifting movements of the magazine unit with respect to the main frame.

16. A typographical machine comprising a main frame having upper and lower tracks extending forwardly and rearwardly thereon, a magazine unit embodying a plurality of superposed matrix magazines, rollers mounted to travel on the upper tracks and pivotally supporting the upper end of the magazine unit on an axis which is shiftable rectilinearly with respect to the main frame, an eccentric shaft mounted to travel on the lower tracks and operative to support and to lift and lower the lower end of the magazine unit, and links connecting said shaft to said rollers and operative to govern the shifting movements of the magazine unit.

17. A typographical machine comprising a main frame, a magazine unit embodying a stack of matrix magazines, rollers supporting one end of said unit on an axis which is shiftable rectilinearly in a direction forwardly and rearwardly of the main frame, a shaft having an eccentric portion movable in a cycloidal path and on which the other end of said unit rests movably whereby said eccentric portion of the shaft, during its movement in said cycloidal path, will lift and lower the respective end of the magazine unit, and links connecting said shaft to said rollers and governing the shifting movements of the magazine unit.

18. A typographical machine comprising a main frame, a magazine unit embodying a plurality of superposed matrix magazines, rollers supporting said unit to shift forwardly and rearwardly with respect to the main frame, a shaft shiftable forwardly and rearwardly with respect to the main frame and embodying an eccentric portion movable in a cycloidal path and engaging the magazine unit to lift and lower its matrix-delivery end while permitting the magazine unit to shift forwardly or rearwardly at its point of engagement with the eccentric portion of said shaft, and links connecting said shaft to said rollers and operative to govern the forward and rearward shifting movements of the magazine unit with respect to the main frame.

19. A typographical machine comprising a main frame having upper and lower tracks extending forwardly and rearwardly thereon, a magazine unit embodying a plurality

of superposed downwardly and forwardly inclined matrix magazines having means for delivering matrices at their lower ends, rollers mounted to travel on the upper tracks and shiftably supporting the upper end of the magazine unit, a shaft mounted to travel on the lower tracks and embodying an eccentric portion movable in a cycloidal path to engage and to lift and lower the lower matrix-delivery end of the magazine unit while permitting the latter to shift forwardly and rearwardly relatively to the eccentric portion of said shaft, and links connecting said shaft to said rollers and operative to govern the forward and rearward shifting movements of the magazine unit. 75

20. A typographical machine comprising a main frame, a magazine unit embodying a stack of matrix magazines, rollers supporting one end of said unit to shift in a forward and rearward direction on said frame, a shaft having an eccentric portion movable in a cycloidal path and on which the other end of said unit rests movably whereby said eccentric portion of the shaft, during its movement in said cycloidal path, will lift and lower the respective end of the magazine unit while the latter is capable of shifting forwardly and rearwardly relatively to said eccentric portion of the shaft, and links connecting said shaft to said rollers and governing the shifting movements of the magazine unit on the main frame. 85

21. A typographical machine comprising a main frame having escapement actuating devices thereon, a magazine unit embodying a plurality of superposed downwardly and forwardly inclined matrix magazines overlying said escapement actuating devices and having escapements for delivering matrices at their lower forward ends, rollers supporting said unit to shift forwardly and rearwardly relatively to the main frame, a shaft shiftable forwardly and rearwardly relatively to the main frame, and having an eccentric portion movable in a cycloidal path and arranged to engage and to lift and lower the matrix-delivery end of the magazine unit while movable in a forward or rearward direction relatively to said unit, and means connected to the magazine unit independently of the engagement of the eccentric portion of said shaft therewith but controlled by said shaft for shifting the magazine unit forwardly or rearwardly relatively to the main frame. 100

In testimony whereof I have hereunto set my hand.

JOHN ROBERT TOMLIN.
